UNITED STATES PATENT OFFICE

ISAAC BARTON, OF WILLIAMSPORT, PENNSYLVANIA.

IMPROVEMENT IN STEAM-GENERATORS.

Specification forming part of Letters Patent No. 140,872, dated July 15, 1873; application filed March 24, 1873.

To all whom it may concern:

Be it known that I, ISAAC BARTON, of Williamsport, in the county of Lycoming and State of Pennsylvania, have invented an Improvement in Steam-Boilers, of which the following is a specification:

This invention mainly relates to return-flue tubular boilers, having a fire-box within them, and consists in a certain peculiarity of construction or novel combinations of parts, including an air-distributing box, hollow bridge-wall, and water legs or sides connected to the bridge-wall, whereby a safe and efficient boiler is produced, easy of repair and economical to work, and with perfect provision as regards distribution of air to assist in the combustion of the escaping gases.

In the accompanying drawing, which forms part of this specification, Figure 1 represents a longitudinal vertical section of a boiler constructed in accordance with my improvement; Fig. 2, a transverse vertical section on the line *x x*; and Fig. 3, a similar section on the line *y y*, but looking in a reverse direction.

Similar letters of reference indicate corresponding parts.

The boiler represented in the drawing is a double return horizontal tubular one of the "locomotive" or portable kind, but the crown-sheet A is of a convex shape, struck from a center above, and of the width of the fire-box B down within which it projects. This shape of the crown-sheet is preferable to a concave one arching upward, inasmuch as not only is that strength obtained which is due to a cylindrical boiler, without the aid of braces or stays, but there is an increased heating-surface as compared with a flat crown-sheet, and the capacity of the boiler may be enlarged without increasing the width of the outside shell or lengthening the latter or flues of the boiler, but by simply lengthening the sides or water-spaces C C and bringing the crown-sheet A further down so as to admit of an increased number of tubes or flues being inserted. On board boats, and where room is an object, this is an important consideration. D is the grate, E the fire-door, and F the ash-pit. G G are the fire-box tubes or flues, and H the back tube-sheet thereof, connected above so as to

form an attachment at right angles or thereabout, with an upper crown-sheet, I.

The fire and heated gaseous products of combustion first return along the fire-box flues G G into a front smoke-box, K, and from thence back through an upper or second set of longer return-tubes, L L, into a rear smoke-box, S, which connects with the chimney. M M represent a row or rows of drop-tubes connected through the upper crown-sheet I with the water-space above. These tubes, which are exposed to the full action of the flame from or in the fire-box, are fitted with circulating pipes b on their inside, open at their bottoms, while the tubes are closed at their lower ends to keep up a circulation and prevent collection of mud or sediment in the tubes. Said drop-tubes add to the capacity of the boiler without adding to the room occupied by the latter. N is a steam-dome, on which may be a man-head, safety-valve, and branch steam-pipe. O is a plate at back of the ash-pit, having a projection on it to carry the grate. This plate may be fitted with a slide or damper to admit cold air into a perforated box or chamber, P, beneath and in rear of the bridge-wall Q, to assist in the combustion of the gases when needed, and which air, by the arrangement shown, will be properly heated to give the best results on mixing with the gases. R R are cross-braces for strengthening the boiler at points above the lower return-tubes or flues. Other stays may also be used, if desired, and the seam of the crown-sheet A either be turned upward or downward, as preferred. The crown-sheet is shown as inclining downward in a rearward direction, to give increased water capacity where the fire is hottest.

The bridge-wall Q is made hollow to form a water-space in communication with the water legs or sides C C. This not only gives increased heating-surface, but promotes circulation. There may be any number of such tubular connections, one in rear of the other. T is a blow-pipe, connecting with the boiler through the lower back portion of the crown-sheet A, and projecting through the rear water leg or side of the boiler, the same serving to carry off mud or sediment collecting on the crown-sheet A.

In some cases—as, for instance, in boilers for sea-going steamers—a single and enlarged upper shell surface, V, may be made to take in or cover two, three, or more convex crown-sheets A and water legs or side spaces between them, as well as outside water-spaces, with a like arrangement of return tubes or flues and accompanying parts heretofore described.

What is here claimed, and desired to be secured by Letters Patent, is—

1. The combination of the double set of return-flues G L, the front and rear smoke-boxes K S, the fire-box B, the crown-sheet A, the water legs or sides C, the back tube-sheet H, and the upper back crown-sheet I, when said

sheets H and I and the other parts above named are arranged in relation with each other, substantially as specified.

2. The combination of the air-distributing box P with the hollow bridge-wall Q and water legs or sides C C, with which said bridge-wall connects, substantially as and for the purposes specified.

In testimony whereof the party hereto has hereunto signed his name before two subscribing witnesses.

ISAAC BARTON.
